UNITED STATES PATENT OFFICE.

AMADORE F. STEPHENSON, OF DUMONT, NEW JERSEY.

DESIGN FOR A POISON-BOTTLE.

47,348.

Specification for Design.

Patented May 11, 1915.

Application filed December 3, 1913. Serial No. 804,514. Term of patent 7 years.

To all whom it may concern:

Be it known that I, AMADORE F. STEPHENSON, a citizen of the United States, residing at Dumont, in the county of Bergen and State of New Jersey, have invented a new, original, and ornamental Design for Poison-Bottles, of which the following is a specification, reference being had to the accompanying drawings, forming part thereof.

The figure is a perspective view of a poison bottle, showing my new design.

The bottle comprises a body portion 1 having a bottom lower bead 2, a neck 3 and a bulged mouth piece 4 on the neck with a

bead 5 between the mouth piece and the adjacent portion of the neck. The body of the bottle is bowed in an outward direction and it is curved directly into the neck and at a point directly beneath the mouth piece 4 the neck 3 is provided with a circular series of horizontal barbed-like projections 6.

I claim:

The ornamental design for a poison bottle, as shown and described.

AMADORE F. STEPHENSON.
